QUEBEC, CANADA

ENGINE-VALVE CONSTRUCTION

Application filed April 23, 1928. Serial No. 272,141.

The invention relates to engine valve construction, as described in the present specification and illustrated in the accompanying drawings that form part of the same.

5 The invention consists essentially of the novel features of construction pointed out broadly and specifically in the claim for novelty following a description containing an explanation in detail of an acceptable 10 form of the invention.

The objects of the invention are to eliminate the complications in the assembly of sleeve valve and in their operation insure the 15 maintenance of gas tight joints; to increase the efficiency and in fact to bring the engine, and particularly the internal combustion engine, up to a high standard of excellence, by simplifying the features of construction, reducing the costs of production and enabling 20 the manufacturer to use metals of the same or different coefficients of expansion, thus making the use of aluminium or such like metal advantageous in the construction of the engine blocks for certain types of engines; to furnish to the public and particularly to the motor trade an expanding sleeve 25 valve that will automatically adjust itself to the varying conditions regarding temperature during the continuous operation of the engine and avoid any leakage of gas, such as at any time may occur where the sleeve and the cylinder are both of predetermined and permanent diametrical dimensions in relation to one another; to facilitate 30 the assembling of the parts of an internal combustion engine of the sleeve valve type and the adjusting of the operating parts; and generally to provide a durable tight and serviceable construction in sleeve valve engines.

In the drawings, Figure 1 is a vertical sectional view of a sleeve valve engine, showing this particular type of sleeve valve.

Figure 2 is a perspective detail of the 45 sleeve removed from the engine cylinder.

Figure 3 is a cross sectional view on the line 3-3 in Figure 2.

Figure 4 is a cross sectional view on the line 4-4 in Figure 2.

50 Figure 5 is a diagrammatic view showing

the relative positions of the sleeve valve interlocking lugs and the piston at the end of the suction stroke.

Figure 6 is a diagrammatic view showing the interlocking lugs of the sleeve valve 55 practically in the same position as in Figure 5, and at the end of the compression stroke.

Figure 7 is a diagrammatic view showing the relative positions of the interlocking lugs 60 of the sleeve valve at the end of an explosion stroke, and in which expansion begins to be in evidence.

Figure 8 is a diagrammatic view showing the relative positions of the interlocking lugs 65 during the operation of the engine at the full expansion of the sleeve valve.

Figure 9 is a vertical sectional view of the engine, showing a modified form of the split sleeve valve.

Figure 10 is a vertical sectional view at 70 right angles to the section illustrated in Figure 9.

Figure 11 is a perspective detail of the sleeve valve illustrated in Figure 9.

Figure 12 is a cross sectional view on the 75 line 12-12 in Figure 9.

Figure 13 is a vertical sectional detail showing the use of an expansion ring in spreading the sleeve valve.

Figure 14 is a perspective detail, showing 80 a modified form of the sleeve valve and illustrating the same with two splits in place of one. Figure 15 is a detail of the split.

Like numerals of reference indicate corresponding parts in the various figures.

85 Referring to the drawings, the engine cylinder, indicated by the numeral 20 is formed at the upper end with the exhaust port 21 and the inlet port 22 as well as an opening 90 for the ignition plug 23.

The sleeve 24 having the port 25 adapted to register respectively with the ports 21 and 22 is formed with a zig-zag longitudinal split 26, and this split forms the interlocking lugs 27 and 28 on either side of the split respectively.

95 The split is preferably diametrically opposite to the operating lug 29, and is secured to or forms part with the said sleeve 24 at its lower end and also diametrically 100

opposite to the port 25 and another port 30 for lower exhaust if required, a registering port 31 for the port 30 being also shown in the cylinder 20 though this is optional.

5 The lugs 27 and 28 are shown as of rectangular shape fitting snugly from side to side between one another, so that ample opportunity is given for expansion and contraction.

10 The sleeve is shown as being operated through the connecting rod 32 pivotally secured to the lug 29 at its upper end and to the crank 33 at its lower end, this crank being operated from the engine crank shaft.

15 In the operation of this form of the invention the sleeve is inserted in the cylinder and joined up to its operating members and moves upwardly and downwardly to open and close the exhaust and inlet ports, 20 and in this connection it may be pointed out that this is a single sleeve engine, with a straight up and down motion, which is made possible by the expansion of the sleeve during the running of the engine.

25 Just so soon as the engine gets well started the sleeve begins to expand and naturally at the point of least resistance, namely the split, the metal springs or spreads, which is tantamount to increasing the pressure of 30 the sleeve on to the cylinder wall. That is to say, the tendency of the sleeve, because of the split is to straighten out and this straightening out effect is accountable for the great pressure on the wall, as the temperature within the cylinder increases as 35 the piston therein continues to reciprocate. It will be seen that notwithstanding the split the natural expansion of the metal will effectually close up all possible passages for 40 the gas, so that in any stroke of the piston or the sleeve there is no chance of the leakage of gas from lug to lug throughout the split, consequently without further complication, such as double sleeves and spiral operations and such like, the result is gained 45 simply by taking advantage of the natural expansion of the metal.

In Figures 9, 10, 11 and 12, the only difference is that the sleeve 34 is mounted in 50 the head 35 of the engine cylinder 36.

The cylinder head converges to a horizontal cylindrical valve chamber in which the sleeve 34 slides, bringing its port 38 on the one side into register with the inlet 55 port 39 on the one hand through the cylinder head or the adjacent exhaust port 40.

The port 41 diametrically opposite the ports 39 and 40 is continually in register with the port 42 leading from the cylinder 60 36 into the head 35.

The sleeve 34 is split longitudinally in the zig-zag line of split 43 forming the interlocking lugs 44 and 45 preferably of rectangular shape, though they may be of any shape desired.

The sleeve 34 is operated by sleeve rod 46, secured to the radially extending arm 27. This rod 46 extends through the gland 49 and is operated by suitable cam or crank mechanism.

70 In the operation of this form of the invention the sleeve 34 is reciprocated in the head 35, bringing the port 38 in register with the port 39, at the beginning of the suction stroke of the piston 50, which operates in the cylinder 36, and in register with the exhaust port 40 at the beginning of the exhaust stroke in between the inlet and exhaust ports 38 being closed at the beginning and during the compression 80 stroke.

The sleeve 34 expands as explained hereinbefore in relation to the sleeve 24 and engages the wall of the sleeve valve chamber in the head 35.

85 In Figure 13 another slightly modified form of the invention is shown, in which the sleeve 51 contains in its inner wall at the upper end the expansion ring 52 which facilitates the expansion of the sleeve 51 90 against a cylinder wall.

The sleeve 51 is longitudinally split at 53, the same as the sleeves already described, and this split has a tendency to widen with the expansion of the ring 52, and in this 95 tendency to widen it engages the wall of the cylinder in which it may be enclosed.

In Figure 14 still another slight modification is shown in which the sleeve 54 is split at diametrically opposite sides showing the split 51, longitudinally running through the sleeve at one side and the split 56 longitudinally running through the sleeve on the other side.

100 These splits form interlocking lugs in 105 precisely the same manner as in all the other forms, these lugs being of any shape desired.

In all of the sleeves oiling grooves may be made as is thought advisable. These 110 grooves may run in any direction and furthermore portions of the bearing surface may be removed for lubrication or other purposes. Then again slots may be made to accommodate the spark plugs, and various changes in shape and form may occur 115 in regard to the invention without departing from the spirit thereof.

In all of the forms shown a gas tight joint 120 is maintained at the ports when closed by the pressure exerted by the sleeve which is allowed to expand radially by means of the expansion split.

This expansion may be caused by the 125 inherent spring qualities in the material of the sleeve or by tempering or other manufacturing processes or by the pressure exerted by resilient rings or other special expansion rings independently of the piston 130

rings contained in the grooves of the piston operating in the sleeve.

What we claim as our invention is:—

In engine valve construction, a sleeve 5 formed of two parts having longitudinal edges forming zig zag splits; and suitable ports, and at the ends ring recesses and expansion rings in said recesses.

Signed at Montreal, Canada, this 11th 10 day of April, 1928.
